APPARATUS FOR INSTRUCTION OR
AMUSEMENT

Nicholas Stephen Krassilnikoff, London, England

Application May 13, 1944, Serial No. 535,453
In Great Britain May 8, 1943

4 Claims. (Cl. 35—40)

This invention relates to apparatus intended primarily for instruction but also capable of use in playing a game.

An object of the invention is to provide apparatus for use in identifying parts of a diagram, such as a map, chart or drawing, which is required to be studied by a pupil, the apparatus requiring manipulation by the pupil in order to enable the said parts to be identified.

More specifically, an object of the invention is to provide such apparatus in which an electrical contact element is engageable by the operator with any of a number of contacts located respectively at the several parts of the diagram required to be identified and in which, when the name of any selected part has been correctly selected from a key list of such parts appearing on the apparatus, a current-responsive signal device, such as a lamp or a bell, will operate, indicating that the operator has correctly related the place on the diagram with its name on the list. When the apparatus is used for instruction, the labour thus required of the pupil in identifying a part of the diagram, or in ascertaining the position on the diagram of a part named in the key list, has the effect of making a more lasting impression on the pupil's memory of the information gained thereby than would mere reference to a diagram bearing directly the identifying legends.

An embodiment of the invention, as applied to apparatus for use in giving instruction in geography, will be described by way of example with reference to the accompanying diagrammatic drawing, in which—

Fig. 1 is a front elevation of the apparatus, the lower part being shown in section on the line 1—1 in Fig. 2, and

Fig. 2 is an "exploded" section on the line 2—2 in Fig. 1.

Referring to Figs. 1 and 2, a panel 10A of electrically insulating material bears on its face a map 11A, and on its back a sheet of electrically conducting foil 30. Place names missing from the map are replaced by contact eyelets 12A clenched in holes in the panel 10A and the foil 30 which serves to bond all the eyelets 12A electrically together. A base plate 16A, also of electrically insulating material, bears on its upper face a sheet 31 of electrically conducting foil having a central aperture and secured by eyelets such as 32. The panel 10A and the base 16A are fastened in spaced relationship by screws 33 and nuts 34 which pass through packing pieces 35 at

the corners, and which bear on the baseplate and panel through the agency of washers 48.

A masking disk 36 of electrically insulating material is accommodated between the panel 10A and the base 16A and is pivotally mounted on a screw 37 which is engaged in a central hole 38 in the panel 10A and locked by a nut 39. The disk 36 is provided with apertures 40 the diameter of which slightly exceeds the bore of the eyelets 12A. The place names missing from the map and replaced by eyelets 12A are set out in a list inscribed around the border 41 of the disk 36, in such a manner that they can be brought into position, one at a time, for display in a notch 42 in the panel, by rotating the disk. The notch 42 provides a convenient space for the operator's finger to engage and move the disk.

A metal washer 43, resiliently engaged on the screw 37, bears on the foil 30, and the head of this screw is connected by a wire 44 to one terminal 21A of a battery 22A the other terminal of which is connected through a current-responsive device 23A, a terminal 21B and a wire 45 to one of the eyelets 32 that secures the foil 31 to the base. A metal contact plug 46, which is a close sliding fit in the eyelets 12A, is anchored to the apparatus by a cord 47.

The apertures 40 in the masking disk 36 are equal in number to the eyelets 12A and are so distributed that, when the disk is set to bring any of the place names inscribed on its border into position for display at the notch 42, one of the apertures 40 will register with the eyelet 12A that corresponds to the selected place name. If now the plug 46 is inserted in the proper eyelet, it will make a connection between the foils 30 and 31 and so close the circuit through the device 23A. If, however, the plug 46 is inserted in any but the proper eyelet, the disk 36 will prevent its making contact with the foil 31 on the base.

I claim:

1. Apparatus for use in identifying parts of a diagram, including a panel bearing the diagram and having a number of electrical contact apertures the sides of which are electrically connected together and which are located respectively at the parts of the diagram to be identified, a perforated mask displaceably mounted behind said panel, a contact plate behind said mask, an electrical circuit including a source of current in series with a current-responsive signal device connected between said contact aperture sides and said contact plate, and a movable contact plug shaped to slide through said contact apertures and pass through said mask

into engagement with said contact plate, said mask being associated with inscriptions of the names of said parts set out in such a manner that adjustment of said mask to a position appropriate for indicating any one of said names brings one of the perforations in the mask into register with the one of said contact apertures that is located at the one of said parts having the name so indicated while the remainder of said contact apertures are masked, so that, if said contact plug is inserted into said contact apertures in succession, said signal device will respond only when said plug is inserted into said one aperture.

2. Apparatus for use in identifying parts of a diagram, including a panel bearing the diagram and having a number of electrical contact apertures the sides of which are electrically connected together and which are located respectively at the parts of the diagram to be identified, a circular perforated mask rotatably mounted behind said panel, a contact plate behind said mask, an electrical circuit including a source of current in series with a current-responsive signal device connected between said contact aperture sides and said contact plate, and a movable contact plug shaped to slide through said contact apertures and pass through said mask into engagement with said contact plate, said mask being associated with inscriptions of the names of said parts set out on a circle concentric with the centre of said mask and so arranged that displacement of said mask into a position indicating a selected one of said names will bring one of the perforations in the mask into register with the one of said contact apertures that is located at the part of said diagram corresponding to said selected name while the remainder of said contact apertures are masked, so that, if said contact plug is inserted into said contact apertures in succession, said signal device will respond only when said plug is inserted into said one aperture.

3. Apparatus for use in identifying parts of a diagram, including a panel of electrically insulating material bearing the diagram on its face and a sheet of electrically conductive foil fixed on its back, a number of metal eyelets which are fixed in apertures in said panel and said foil whereby said eyelets are electrically bonded together and which are located respectively at the parts of the diagram to be identified,

5 a perforated mask displaceably mounted behind said panel, a contact plate behind said mask, an electrical circuit including a source of current in series with a current-responsive signal device connected between said eyelets and said contact plate, and a movable contact plug shaped to slide through said eyelets and pass through said mask into engagement with said contact plate, said mask being associated with inscriptions of the names of said parts set out in such a manner that adjustment of said mask to a position appropriate for indicating any one of said names brings one of the perforations in the mask into register with the one of said eyelets that is located at the one of said parts having the name so indicated while the remainder of said eyelets are masked, so that, if said contact plug is inserted into said eyelets in succession, said signal device will respond only when said plug is inserted into said one eyelet.

4. Apparatus for use in identifying parts of a diagram, including a panel of electrically insulating material bearing the diagram on its face and a sheet of electrically conductive foil fixed 25 on its back, a number of metal eyelets which are fixed in apertures in said panel and said foil whereby said eyelets are electrically bonded together and which are located respectively at the parts of the diagram to be identified, a circular 30 perforated mask rotatably mounted behind said panel, a contact plate behind said mask, an electrical circuit including a source of current in series with a current-responsive signal device connected between said eyelets and said contact plate, and a movable contact plug shaped to slide through said eyelets and pass through said mask into engagement with said plate, said mask having inscriptions of the names of said parts set out thereon on a circle so as to be capable 35 of being selected by displacement of said mask for display one at a time at an indicating position in said panel, the perforations on said mask being so distributed that when any one of said names is displayed, one of the perforations in said mask is in register with the one of said eyelets corresponding to said one name while all the rest of said eyelets are masked, so that, if said contact plug is inserted into said eyelets in succession, said signal device will respond only when said plug is inserted into said one eyelet.

NICHOLAS STEPHEN KRASSILNIKOFF.
